UNITED STATES PATENT OFFICE.

HUBERT C. HART, OF UNIONVILLE, CONNECTICUT.

DESIGN FOR A FORK.

SPECIFICATION forming part of Design No. 14,946, dated April 8, 1884.

Application filed February 7, 1884. Term of patent 7 years.

To all whom it may concern:

Be it known that I, HUBERT C. HART, of Unionville, in the county of Hartford and State of Connecticut, have invented and produced a new and original Design for Forks; and I do hereby declare that the following is a full, clear, and exact description of the invention, which will enable others skilled in the art to which it appertains to make and use the same, reference being had to the accompanying drawings, which form a part of this specification, and in which—

Figure 1 is a front view of my newly-designed fork. Fig. 2 is an edge view of the same; and Figs. 3, 4, 5, and 6 are cross-sections on the dotted lines in Fig. 1, *x x*, *y y*, *z z*, and *n n*, respectively.

Similar letters of reference indicate corresponding parts in all the figures.

My design relates to forks for table use, and the handle A is tapering upward in width, and is slightly flattened at the lower end, and at the upper end of the handle is a groove, B, above which is a bead or enlargement, C, formed by the aforementioned groove and another groove,

D, above the bead, the said bead having a narrow flat edge, E. A bulb, F, is formed above the upper groove and the flat sides G of the shank H form depressions I at the upper end of the bulb, passing over in the said flat sides, while the edges of the shank pass gradually over into the sides of the bulb.

Having thus described my design, I claim and desire to secure by Letters Patent of the United States—

The design for forks, consisting of a handle tapering in width toward its upper end and having its lower end flattened, a groove at the upper end of the handle, a bead above the groove having a narrow flat edge, a groove above the bead, and a bulb having the flat sides of the shank forming depressions at its upper end, as shown and set forth.

In testimony that I claim the foregoing as my own I have hereunto affixed my signature in presence of two witnesses.

HUBERT C. HART.
